UNITED STATES PATENT OFFICE.

VICTOR O. STROBEL, OF PHILADELPHIA, PENNSYLVANIA.

HOT-BLAST STOVE.

SPECIFICATION forming part of Letters Patent No. 358,500, dated March 1, 1887.

Application filed May 15, 1886. Serial No. 202,330. (No model.)

To all whom it may concern:

Be it known that I, VICTOR O. STROBEL, of Philadelphia, Philadelphia county, Pennsylvania, have invented certain new and useful 5 Improvements in Hot-Blast Stoves, of which the following is a specification.

This invention pertains to regenerative hot-blast stoves for heating the blast employed in blast-furnaces, &c., and the improvements will 10 be readily understood from the following description, taken in connection with the accompanying drawings, in which—

Figure 1 is a vertical section of a single-pass regenerative stove, illustrating one feature of my improvements; Fig. 2, a horizontal section of the same; Fig. 3, a vertical section of a pair of stoves illustrating my improvements, the left-hand stove of the pair being shown as a two-pass stove with its chimney-connection at the top, while the right-hand stove of the pair is shown as a three-pass stove with its chimney-connection at the bottom; Fig. 4, a plan of the same; Fig. 5, a vertical section and elevation of a group of 20 three stoves illustrating my improvements, the stove being shown as of the single-pass type with chimney-connection at the tops; Fig. 6, a horizontal section of the same; Fig. 7, a side elevation of the same, and Fig. 8 a 25 plan of the same.

Regenerative hot-blast stoves are sometimes arranged with a single pass—that is, the heating gases or blast being heated enter at one end of the stove and move directly toward 30 and out at the other end of the stove—and sometimes, again, with several passes, up and down which the heating gases or blast being heated pass alternately from the inlet to the outlet, and the chimney-connection and the 35 blast and gas connection are sometimes arranged at the bottom of the stove and sometimes at the top.

My improvements are applicable to stoves constructed in any of these ways.

40 In the drawings, A represents a hot-blast stove containing regenerative brick-work to be heated by the passage through it of burning gases, and to give up heat to blast passing through it; B, the chimney-connection of the stove, this connection being shown as at the top of the stove, except in the case of the

right-hand end stove of Fig. 3, where the chimney-connection is at the bottom, the chimney-connection being provided, as usual, with a valve by which the communication between 55 stove and chimney may be cut off; C, the cold-blast inlet, provided with the usual valves, by which the cold blast enters the stove, such inlet being located, as usual, near the chimney-connection, whether at the top or bottom of 60 the stove; D, the hot-blast outlet, provided with the usual valves, by which the blast after passing through the stove and becoming heated leaves the stove, such hot-blast connection being located at the point in the stove most 65 distant from the cold-blast inlet; E, a combustion-chamber, consisting of a structure separated from the stove but connected therewith at a point most distant from the chimney-connection of the stove; F, the gas-inlet 70 to the combustion-chamber, such inlet communicating through a valve with a gas-main, and provided, if desired, with a gas-burner for securing a proper diffusion of the gas and air of combustion admitted with it, it being 75 essential that air for combustion should be admitted to the combustion-chamber to unite with the gas; and G, a valve serving to close or open the connection between the combustion-chamber and the stove, there being one 80 of these valves for each of the stoves with which the combustion-chamber is connected.

The gas-burner F referred to may, with excellent satisfaction, be of the kind shown in United States Letters Patent No. 244,746. 85

In Fig. 1 there is but a single stove, and this stove is provided with a combustion-chamber separated from but connected with the stove structure. The stove has its chimney-connection at the top, and the burning gases 90 are admitted at the bottom. The gas and air of combustion are admitted at the base of the combustion-chamber, which is a low cylindrical structure, and in order to give volume to the combustion-chamber and length to the 95 path of the gases before they reach the stove the combustion-chamber is provided with an up-and-down pass by means of a central partition-wall reaching from the base of the combustion-chamber to near the roof of the same. 100 When the stove is to be heated, the chimney-valve is to be opened and the hot and cold

blast valves closed and the valve G open. Gas and air of combustion enter the combustion-chamber and mingle and go into combustion, and rise and turn over the partition-wall and 5 pass to the stove, and thence up the regenerative brick-work and out of the chimney. By the time the heating-gases have entered the stove they have reached a substantially perfect stage of combustion, and the entire regenerative work of the stove becomes thereby subjected to the action of heating-gases in perfect combustion as distinguished from gases whose combustion is in a merely progressive state of development. By this means a superior efficiency 10 is given to the stove with a comparatively small amount of regenerative brick-work. The combustion-chamber is lined with refractory material, and when the lining becomes destroyed by use it may be easily repaired without reference to the condition of the brick-work of the stove proper, a suitable man-hole being preferably provided in the combustion-chamber.

When the stove is under blast, the chimney-valve and the valve between the combustion-chamber and stove are closed, and consequently the blast does not enter the combustion-chamber. The combustion-chamber is therefore not subjected to those extremes of temperature represented by the gas going into combustion and by the air-blast being heated. As the combustion-chamber need never necessarily be subjected to the blast-pressure, it is obvious that it may be of comparatively weak 35 and economical construction.

In the constructions illustrated in Figs. 3 and 4 a single combustion-chamber is made to answer for two stoves. Of the two stoves the one at the left is a two-pass stove, while the 40 one at the right is a three-pass stove, both having the gas-inlets and the hot-blast outlets at the top of the stove. I do not contemplate at present the combination in such an arrangement of two stoves of dissimilar character, but I illustrate the matter in this manner in order to render clear the applicability of the system to various arrangements of stoves. In 45 this arrangement of Figs. 3 and 4 one of the stoves is under blast, its communication with the combustion-chamber being entirely cut off, while the other stove is under gas, its blast-connection being entirely cut off. In this arrangement the combustion-chamber will always be under gas, the change from one stove 50 to the other being effected by manipulating the various stove-valves. In the arrangement shown in Figs. 3 and 4 volume and length of path in combustion-chamber are secured by the height of combustion-chamber incident to the 55 gas-inlets of the stove being at their tops.

In Figs. 5, 6, 7, and 8 I show a combination of one combustion-chamber with three stoves, the three stoves having the gas-inlets at their bases. In this case, as in the case of the structure 60 shown in Figs. 1 and 2, volume and length of path in the combustion-chamber are secured by making the combustion-chamber low and

large, and forming it with an up-and-down pass. In the present case the double pass is formed in the combustion-chamber by an annular inner wall, the gas and air for combustion entering within this inner wall and turning over its top and passing downward and out through the connection or connections to whichever stove or stoves may be under gas. 75 75

In all hot-blast stoves of the regenerative type, as usually constructed, the combustion-chamber is arranged within the structure of the stove proper, and becomes subjected to the extremes of heat and cold, represented by the 80 gas in combustion and in the incoming cold air, and the combustion-chamber is also subjected to the full pressure of the blast. Such structures are obviously radically deficient in the peculiar qualities inherent in my improvements. In ordinary pipe-stoves the furnace or combustion-chamber is of course separate from the pipes through which the blast passes in being heated; but the entire construction and mode of operation of these pipe-stoves are 85 so radically different from the construction and mode of operation involved in regenerative stoves that comparisons need not be made, it being obvious that no part of the gas-path in the pipe-stoves becomes subjected to the pressure of blast or to the two extremes of heat and cold above noted. Regenerative stoves have been constructed in double vertical form, somewhat like an inverted letter U, one limb of the structure forming the combustion-chamber; but this limb was not arranged to be cut off from the regenerative work, and the combustion-chamber therefore becomes subjected to the full pressure of the blast and to the extremes of heat and cold above noted. By my 90 improvements I avoid these exposures, and thereby secure a combustion-chamber not subject to the usual action of destruction, and at the same time peculiarly adapted for economical maintenance. 95 100

It has been proposed to provide regenerative hot-blast stoves with regenerative chambers for heating the gases preliminary to admitting the gas to the combustion-chamber in which it is burned in the stove. In such devices as proposed the hot-blast stove in which the gases were burned were provided with combustion-chambers in which the gas was to be burned, and with inlets for the gas and air of combustion. The system might be briefly 115 described as a regenerative hot-blast stove for heating the gas before it was passed into the combustion-chamber of another stove to be burned. My invention is broadly distinguishable from such proposed system, inasmuch as 120 the combustion-chamber employed by me is not a preheater of the gas to be burned, and no other combustion-chamber is employed in the regenerative portion of the stove, and no air of combustion, and consequently no inlet 125 for such air, is necessarily employed in the regenerative work proper. I do not necessarily preheat the gas before admitting it to my combustion-chamber. I take the gas in the 130

condition in which it may come, whether it be at usual temperature or previously heated in suitable apparatus, it being no part of the office of my combustion-chamber to elevate the 5 temperature of the gas before ignition.

I claim as my invention—

1. A hot-blast stove containing regenerative work, connections thereto for an inflow and outflow of blast, and provided with valves, a chimney-connection thereto provided with a valve, a combustion-chamber exterior to the stove, a gas-inlet to the combustion-chamber, a connection leading from the combustion-chamber to the stove, and a valve in said last-15 mentioned connection, combined substantially as and for the purpose set forth.
2. A hot-blast stove containing regenerative work, connections thereto for the inflow and outflow of blast, and provided with valves, a chimney-connection thereto provided with a valve, a combustion-chamber exterior to the stove, a connection leading from the base of the combustion-chamber to the stove, a valve in the last-mentioned connection, a gas-inlet 25 at the base of the combustion-chamber, and a partition-wall rising from the base of the combustion-chamber toward the roof thereof between the gas-inlet and the gas-connection to the stove, combined substantially as and for 30 the purpose set forth.

3. A hot-blast stove containing regenerative work, connections thereto for the inflow and outflow of blast, and provided with valves, a chimney-connection thereto provided with a valve, a combustion-chamber exterior to the 35 stove, a connection leading from the combustion-chamber to the stove, a valve in said last-mentioned connection, a gas-inlet to the combustion-chamber, and a gas-burner disposed exterior to the combustion-chamber at said 40 gas-inlet and connecting with a source of gas and air supply, combined substantially as and for the purpose set forth.

4. Two or more hot-blast stoves containing regenerative work, connections thereto for the inflow and outflow of blast, and provided with valves, chimney-connections thereto provided with valves, a combustion-chamber, a gas-inlet to the combustion-chamber, connections leading from the combustion-chamber to the 45 stoves, and valves in said last-mentioned connections, combined substantially as and for the purpose set forth.

VICTOR O. STROBEL.
